[57] CLAIM

The ornamental design for a microphone mount, as shown and described.

DESCRIPTION

FIG. 1 is a perspective view of a microphone mount showing our new design; the broken lines are shown for illustrative purposes only;

FIG. 2 is a front elevation thereof;

FIG. 3 is a rear elevation thereof;

FIG. 4 is a top plan view thereof;

FIG. 5 is a right side elevation thereof;

FIG. 6 is a bottom plan view thereof; and

FIG. 7 is a cross section taken on line 7—7 of FIG. 2. The appearance of the left side is a mirror image of the appearance of the right side shown in FIG. 5.

The internal slot behind the U-shaped slot of FIG. 2 is also U-shaped as indicated in FIGS. 4 and 7, but its U-shaped appearance is not readily perceptible upon observation of the exterior of the MICROPHONE MOUNT, so the U-shape thereof is not considered an important feature of the design.
